UNITED STATES PATENT OFFICE.

RAYMOND J. McBRENN, OF BROOKLYN, NEW YORK.

TONGUE-AND-SLOT INTERLOCK.

1,281,615.

Specification of Letters Patent. Patented Oct. 15, 1918.

Application filed March 14, 1918. Serial No. 222,310.

To all whom it may concern:

Be it known that I, RAYMOND J. McBRENN, a citizen of the United States, residing in the city of New York, borough of Brooklyn, county of Kings, and State of New York, have invented certain new and useful Improvements in Tongue-and-Slot Interlocks, of which the following is a specification.

10 This invention relates to a tongue-and-slot interlock for any and all purposes and of whatever material made.

The object of the invention is to provide an exceedingly simple construction of the 15 kind in question.

In the accompanying drawings forming a part thereof,

Figure 1 is a plan view of a portion of a tongue-receiving member; and

20 Fig. 2 is a plan view of the tongue.

Fig. 3 is a plan view of the tongue-receiving member and tongue in an interlocked assemblage.

25 Fig. 4 is a sectional view at line 4—4 of Fig. 3.

Referring to the drawings, 1 is a tongue-receiving member having a straight slot 2 the length of which slightly exceeds the width of the tongue and the width of which 30 slightly exceeds the thickness of the tongue, whereby the tongue can be readily inserted through the slot. That edge wall of slot 2 which is toward the tongue is indicated by 3.

The tongue shank 4 is formed toward its 35 free end or head 5 with opposite alined straight edge recesses 6 each extending only part way across the width of the tongue, whereby the latter is formed with a neck 7 that is bent to bring the body of the 40 tongue and its head at different levels so that in the assemblage of the members the shank portion of the tongue will be in flatwise contact with one side of the tongue-receiving member, and a part of the head of

the tongue will be in flatwise contact with 45 the opposite side of such member, the bent neck forming a shoulder a surface of which when the coupled members are strained apart abuts against so much of the slot wall 3 as is opposed to the neck; but to obtain 50 a practically continuous abutment of the tongue across its entire width on the outward slot wall 3, when the members are coupled the lateral ends 7^a of the tongue head 5 are depressed below the level of the tongue 55 head in front of the neck, as indicated by the bends 8, extending lengthwise of the tongue head and spaced laterally apart, so as to bring the front edge wall 9 of each recess 6 against the edge wall 3. Forward of 60 the tongue 7 the tongue head is of one level, and at each side of such level the end portions 7^a of the tongue head are alined at a different level.

This invention is particularly applicable 65 in sheet and other metal structures. The contours of the two members may be widely varied and each may be provided with any suitable means for securing them to parts to be detachably coupled.

70 What I claim is:

An interlocking device comprising a tongue-receiving member provided with a tongue-receiving slot which has a straight edge toward the tongue; and a tongue having a head, formed by opposite edge recesses each having a straight edge toward the free end of the head, and a bent neck between the edge recesses, the free lateral ends of the head being at a level to permit their straight edges to abut against said straight edge of the slot when the members are assembled, the neck being then through the slot, and both members then being in flatwise contact.

75 80 85 In testimony whereof I have hereunto set my hand this 25th day of February, 1918.

RAYMOND J. McBRENN.
